UNITED STATES PATENT OFFICE

154,753

DESIGN FOR A COLLAPSIBLE TABLE TRIPOD

John S. Denison, Pekin, Ill., assignor to Denison Industrial Corp., a corporation of Illinois

Application August 3, 1948, Serial No. 147,916

Term of patent 14 years

(Cl. D61—1)

To all whom it may concern:

Be it known that I, John S. Denison, a citizen of the United States, residing at Pekin, in the county of Tazewell and State of Illinois, have invented a new, original, and ornamental Design for a Collapsible Table Tripod, of which the following is a specification, reference being had to the accompanying drawings, forming a part thereof.

In the drawings:

Fig. 1 is a plan view of a collapsible table tripod, showing my new design;

Fig. 2 is a side elevation of the tripod looking from the bottom of the sheet in Fig. 1;

Fig. 3 is a plan view of the tripod in collapsed position; and

Fig. 4 is a side elevation of the tripod in collapsed position.

I claim:

The ornamental design for a collapsible table tripod, as shown and described.

JOHN S. DENISON.
